(57) **CLAIM**

The ornamental design for a shopping bag, as shown and described.

DESCRIPTION

FIG. 1 is a top perspective view of a shopping bag, showing my new design;

FIG. 2 is a front side perspective view thereof;

FIG. 3 is a right side perspective view thereof;

FIG. 4 is a top perspective view thereof with the interior base fully lifted and the bag completely collapsed;

FIG. 5 is a right side perspective view thereof with the bag completely collapsed;

FIG. 6 is a bottom perspective view thereof;

FIG. 7 is a bottom perspective view thereof with the bag completely collapsed;

FIG. 8 is a second top perspective view thereof with the interior base fully lifted and the bag partially collapsed;

FIG. 9 is a rear side perspective view thereof; and,

FIG. 10 is a third top side perspective view thereof with the interior base partially lifted.

The broken lines shown in the drawings illustrate portions of the shopping bag and form no part of the claimed design.

1 Claim, 10 Drawing Sheets
